UNITED STATES PATENT OFFICE.

ROBERT JEFFRIES ROBERTS, OF BOSTON, MASSACHUSETTS, ASSIGNOR TO
ROBERT JAMES MILLER, OF SAME PLACE.

WALKING-TRACK FOR GYMNASIUMS.

SPECIFICATION forming part of Letters Patent No. 358,483, dated March 1, 1887.

Application filed October 20, 1886. Serial No. 216,786. (No model.)

To all whom it may concern:

Be it known that I, ROBERT JEFFRIES ROBERTS, of Boston, in the county of Suffolk, of the Commonwealth of Massachusetts, have 5 invented a new and useful Improvement in Walking-Tracks for Gymnasia; and I do hereby declare the same to be described in the following specification, and represented in the accompanying drawing, which is a vertical 10 section of a walking-track of my invention, the nature of which is defined in the claim hereinafter presented.

In constructing my said track I first evenly spread upon a wooden floor a layer of what 15 is termed "boiler-felt" or other like yielding material, which I fasten to the floor by glue interposed between them and applied to the entire under surface of such covering. Next I stretch firmly over and upon the whole upper 20 surface of the yielding covering a layer of canvas or cotton-duck and secure it in place by nails driven through it close to its edges and into the wooden floor. Next I cover the upper surface of such canvas or duck with a 25 series of coats of oil-paint—generally five in number—allowing each after its application to dry before the next one is spread upon it. In this way I form a track that is not only yielding to the feet of a pedestrian, but is water and dust proof, as any water applied to it 30 for washing it cannot get through it to cause decay or injury to the elastic or yielding covering. Before applying the canvas to the felt

the latter should be rolled down with a heavy garden-roller.

In the drawing, A denotes the floor; B, the yielding or elastic covering or backing of felt; C, the canvas or cotton-duck lining, and D D D D the several coats of oil-paint.

A walking-track made as above described 40 has been found in practice to be highly useful.

I am aware that it is not new to place under a common ingrain or Brussels carpet a layer of felt, and also that it is not new to cover a sheet of canvas with paint. Consequently I do 45 not claim such. I am not aware, however, that a felt backing has ever before been used under a painted or oil-cloth carpet, such a carpet being affixed directly to a floor, and is inelastic, and in such condition will not 50 answer for a walking-track.

I therefore claim—

As a new or improved manufacture, a gymnasium walking-track, substantially as described, consisting of a wooden floor, a layer 55 of glue, one of thick felt or an elastic or yielding material fastened by such glue on its entire under surface to the floor, a covering of canvas or duck, and a series of coats of oil-paint applied to each other and having the 60 lowest one applied directly to the upper surface of the canvas, all essentially as specified.

ROBERT JEFFRIES ROBERTS.
